UNITED STATES PATENT OFFICE

148,377

DESIGN FOR AN EGG RACK

John J. Meehan, Vallejo, Calif.

Application November 18, 1946, Serial No. 134,852

Term of patent 14 years

(Cl. D44—10)

To all whom it may concern:

Be it known that I, John J. Meehan, a citizen of the United States, residing at Vallejo, in the County of Solano and State of California, have invented a new, original, and ornamental Design for an Egg Rack, of which the following is a specification, reference being had to the accompanying drawing, forming part thereof.

The figure is a perspective view of an egg rack, showing my new design.

I claim:

The ornamental design for an egg rack, as shown.

JOHN J. MEEHAN.
